(57) **CLAIM**

The ornamental design for an english letter light, as shown and described.

DESCRIPTION

FIG. 1 is a front perspective view of an english letter light showing our new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a front perspective view of the leftmost part of the english letter light shown in FIG. 1;

FIG. 10 is a front perspective view of the middle part of the english letter light shown in FIG. 1;

FIG. 11 is a front perspective view of the rightmost part of the english letter light shown in FIG. 1; and,

FIG. 12 is an enlarged view taken from a circle part in FIG. 4.

The dashed broken lines circles in FIG. 4 and FIG. 12 define the bounds of the enlargements and do not form part of the claimed design.
